CONVEYER SYSTEM

Norman H. Preble, Grosse Pointe, Mich., assignor
to Jervis B. Webb Company, Detroit, Mich., a
corporation of Michigan

Application May 14, 1936, Serial No. 79,715

9 Claims. (Cl. 198—181)

This invention relates to conveyers and has a particular application to the type thereof employed in the foundry and allied arts for transportation of molds, or other articles, where it is imperative that the movement be steady and free from jolting, jarring or appreciable vibration.

In any conveyor system of material length there is a tendency toward uneven motion, or so-called "surging," which has always been a major problem in conveyer construction. This tendency to surge may result from many different causes often difficult to both determination and remedy. Developments in the conveyer art have resulted in marked improvement in operation and have enabled the use of installations of great length to operate with a uniformity of travel entirely practical for general use. The provision of a plurality of drives automatically responsive to change in load along the line of travel and also automatically cooperating to maintain a uniform rate of travel for the entire conveyer has been a major contribution in this regard. However where the requirements are very rigid with respect to the necessity for eliminating vibration or surge, such as are met with for a mold conveyer, further improvement is essential.

It is therefore a major object of the present invention to provide a conveyer system suitable for use in installations where steady and vibrationless operation is a primary requirement.

More specifically it is an object of the present invention to provide a conveyer with tracks adequately supported, preferably on a floor, and with this rigid and substantially level track system as a foundation to provide load carrying and driving units acting in combination to effect an even and steady motion which will satisfy most exacting requirements.

In carrying out the above it is a further object to provide a main conveying chain, for operation parallel with the aforementioned track, having guide provision at curves in the line of travel in the form of a plurality of guide rollers located tangent to the desired path. A roller bearing curve with a minimum of friction is thereby provided, but in addition the positive guiding of the chain is assured by provision of a unique shape of the rollers at the curves which insures holding the chain in its curved path against movement vertically of the roller regardless of the portion of the chain which contacts the said roller.

It is a further object to provide at certain of

the curves in the line of travel, in combination with the aforementioned guide means, a spring take-up mechanism whereby the driving chain is kept uniformly taut but nevertheless allowing enough resilience to prevent roughness of operation which might otherwise result with a chain held taut by a rigid support.

It is a further object to provide a conveyer system of such construction as to more perfectly maintain an even and steady predetermined rate of travel.

Further to provide for smoothness of operation, it is an important object to so construct the load carrying units operating upon the tracks that the wheeled trucks thereof are connected to the conveying chain and the conveyed platforms in such manner that the wheels of the trucks will always be free to follow smoothly a curve in the line of travel without jarring the conveyed platforms or without exerting any material twisting action tending to bind the chain.

The above and other objects of the invention will appear more fully from the following more detailed description and by reference to the accompanying drawings forming a part hereof and wherein—

Fig. 1 is a general plan view of a satisfactory practical example of a conveyer assembly constructed in accordance with the principles of the present invention showing a part of the endless chain system and in partial detail one of the driving units and also showing a spring take-up at one turn in the conveyer's line of travel;

Fig. 2 is an enlarged plan showing two of the trucks which support the chain and a pallet or carrying platform which forms one conveyer carrying unit. The figure shows the trucks in position for operation on a curved portion of the track;

Fig. 3 is a transverse section on the line 3—3 of Fig. 2 and shows the connection between the chain and a platform supporting truck;

Fig. 4 is a vertical section on the line 4—4 of Fig. 3 and also shows the connection between the chain and a truck;

Fig. 5 is a plan view of one of the curve sections showing the spring take-up and the connection of the curve section to the straight section of the track, also the rollers for guiding the driving chain on the curve;

Fig. 6 is a vertical section on the line 6—6 of Fig. 5;

Fig. 7 is a vertical section on the line 7—7 of Fig. 5;

Fig. 8 is a section on the line 8—8 of Fig. 5

and shows the location of the guiding roller between the tracks at a turn in the conveyer travel;

Fig. 9 shows a longitudinal sectional view on the line 9—9 of Fig. 1 of one of the caterpillar driving units which is supported in a pit below the tracks.

Fig. 10 is a section on line 10—10 of Fig. 1 and shows an end view of the driving unit, the longitudinal view of which is shown in Fig. 9 10 and particularly shows the tracks supporting the driving unit frame.

Referring to Fig. 1 there is shown a general view of a conveyer installation with an endless track system, which, as indicated by the sectional representation, might be of considerable length and follow any desired path of travel required by the layout of the manufacturing establishment in which it is used. Only one driving unit 20 is shown in Fig. 1, but it is to be understood that a plurality of such units located at various points in the line of travel is intended to be used, the number depending upon the length of the system and the conditions of the installation.

25 In general the system shown in Fig. 1 comprises tracks 21—22 upon which two-wheeled trucks 23 (see Fig. 2) are operated, said trucks being driven from a main conveying chain 24 located between the tracks, the chain in turn being driven by the aforementioned driving units 20. Each pair of trucks 23 supports a pallet or platform 25 for carrying the loads to be conveyed. The trucks 23, by their connection between the tracks with the driving chain, also serve as a means of support for the said chain. On straight sections of the conveyer path no other support or guide for the chain is required as the trucks and their supporting tracks will hold the chain in proper alignment. However, at 40 curves in the line of travel the trucks and tracks will no longer be adequate to hold the chain in the desired path, therefore chain guide rollers are provided to engage the chain inside of the curve. On the 180° curves a spring take-up is 45 incorporated with the guide roller unit in the form of a platform shown at 26 in Fig. 1. Said platform unit with the curved track section and roller guide carried thereby is mounted for limited longitudinal movement relative to the adjacent straight track sections under the control of a plurality of springs thereby providing for 50 take-up of slack in the chain as well as affording a resilience for the chain drive essential for smooth operation.

55 The several cooperating units of the system shown assembled in Fig. 1 have for clarity been grouped for more detailed description under sub-headings as follows:

Load carrying units (Figs. 2, 3 and 4).
60 Spring take-up, slip joints and guide rollers (Figs. 5, 6, 7 and 8).
Driving units (Figs. 9 and 10).
Operation.

Load carrying unit

65 Figs. 2, 3 and 4 show assembly and details of a single load carrying unit comprising one pallet or platform 25 supported upon a pair of trucks 23, each of said trucks being provided with suitable connection to the main conveying chain 24. Each supporting truck unit 23 comprises a main shaft 31 upon which are mounted conventional flanged wheels 32 properly spaced to operate on the double track system. On the main shaft 70 31 between flanged wheels 32 is built up a sup-

porting structure made up from standard structural shapes or castings such as a pair of angles 33 welded or otherwise suitably secured to the shaft 31, one angle 33 being located just inside each flanged wheel 32. A second pair of angles 34 are symmetrically spaced nearer the center of said shaft, the supports thus formed by angle pairs 33 and 34 being bridged and secured together by a plate 36. As shown best in Fig. 2 each structural angle member 33 extends a material distance to front and to rear of the shaft 31 and near each end of said angle member 33 there is mounted a so-called thrust washer 35, there being four such washers on each truck unit. These washers 35 are of material area and serve 15 as supporting pads for the pallet or platform 25 while allowing the surfaces of washers 35 to slide on the under surface of said pallet when required in turning, as will later more fully appear. The means to secure each truck 23 to the conveying chain 24 connects to the central portion of the shaft 31 between the downwardly projecting angles 34 by a loose fitting tube 37 of sufficient length to form a suitable bearing. Welded or otherwise suitably secured to the tube 37 is 20 a downwardly projecting plate 38 having a plate 39 secured at its lower end of construction suitable for effecting a connection to a link of the conveying chain 24, specifically shown as connecting plate 39, to threaded projections of pins 30 40 by nuts and washers 41, 42.

The above detailed construction provides truck units 23 spaced at definite intervals along the conveyer tracks and connected to conveying chain 24. Provision is made to secure a pallet or carrying platform 25 on each pair of trucks 23 by pins 47 each of which fits in a hole 46 located centrally between the wheels on each truck, said pins also being fixed and welded in holes provided in blocks 48 suitably secured to the underside of 40 pallet 25. The pallet 25 is preferably made up of a flat plate 49 forming the top, with suitable reinforcing angles 50, although various forms of construction might be employed.

It is noted that each truck 23 supporting an 45 end of a pallet 25 is secured to a link of chain 24 and also each truck 23 has freedom of movement around the center of pin 47 as an axis. Therefore when the assembly as shown in Fig. 2, encounters a curve in the track and the chain 24 is 50 guided around said curve the turning of the chain link will also turn the truck 23 about pin 47, the surface of washers 35 sliding on the smooth under surface of plate 49 of pallet 25. With the chain properly guided in a manner to be later 55 described, it is apparent that the trucks 23 will be turned by the link of the chain to which each is attached and if the chain is so guided that the link is kept substantially tangent to the curve being turned then the truck wheels 32 will turn 60 the curve smoothly without binding the wheel flanges on the curved tracks.

Spring take-up, slip joints, and guide rollers

As shown in Figs. 5, 6, 7 and 8, there is provided a spring take-up at certain of the turns in the line of travel of the conveyer. To provide for this take-up the entire curve of the track together with a roller turn chain guide are mounted upon a platform 60. The curved sections of the track 64, 62 are provided at their ends with sliding joints 63, 64, the location of the joints being at a point before the start of the curve so that movement of the platform in a direction parallel with the straight section of the tracks will effect a 75

tightening of the chain. The mounting of the platform for the longitudinal movement is provided for by a construction located in a pit 65 below the floor line, a cross sectional view of the pit being shown in Figs. 6 and 7. To carry out this purpose the platform 60 is mounted upon a plurality of rollers 66 supported below the platform 60 on suitable channel members 67, 68, two such units being shown dotted in the plan view of Fig. 5. At the bottom of the pit, as shown in Fig. 7, track members 69 are suitably secured to the bottom of the pit. It is apparent that with this construction the platform 60 is mounted for movement to the right or the left, as shown in Fig. 5, to slide the track slip joints 63 and 64 to tighten or slacken the chain 24. Slip joints 63, 64 are constructed by cutting away complementary halves of the joined ends of the track as shown. To keep the platform properly located and to prevent the transverse twisting thereof by the driving load on the chain, suitable rollers 74 are secured to the structural members under the platform 60 and operate against metal angles 75 provided at the edge of the pit, all of which is shown best in Fig. 7.

For the purpose of guiding the conveying chain 24 around the curve a roller turn comprising a plurality of rollers 80 located on the inside of the curve, as shown in Fig. 5, is provided. The periphery of each of these rollers is located tangent to the curve to be followed by the driving chain. A detail view of the support for one of these rollers is shown in Fig. 8, and it is therein shown that a bracket 81 is built up on the track 62 so disposed as to locate the roller 80 for rotation on a suitable pin 82. The roller 80 has a shape such that the conveying chain 24 will be prevented from slipping thereon, such as annular projections 83 and 84 as shown in Fig. 9. It will be noted that projections 83, 84 are beveled to such shape and are so located that a substantially V-shaped guide is provided at the center of the roller thus forming a guide effective for the closed links of the chain. Furthermore, the outer edges of the projections 83, 84 are so located that they will fit between the open links of the chain thereby completing a positive guide for the chain regardless of the portion thereof in contact with the roller.

The platform 60 is held in place and chain tension maintained by a plurality of spring connections between the pit and transverse members 87 designated generally as 88 and made up of a bolt 89 having its end secured to the pit by any suitable means and projecting through one of the structural members 87 below the platform 60. On the projecting end of the bolt 89 is a spring 90 held against the structural member by a nut 91 and washer 92. A plurality of spring units 88 are used as indicated in Fig. 5 with suitable openings 93 and cover plates 94 to enable adjustment of the spring connections 88 thereby to change the tension exerted to move the platform 60 towards the left, to take up the slack in the chain 24.

It is noted that Fig. 5 shows substantially one half of the platform 60, it being understood that the unit is symmetrical.

Driving unit

One or more driving units 20 are provided to insure adequate drive, depending upon the length of the conveyer system. Each of these units, as shown in Figs. 1, 9 and 10, are so constructed as to be below the tracks 21, 22, a pit 10 of sufficient depth to suspend a carrying frame 11 being pro-

vided. On this frame the motor 112, speed changing unit 113 and gear box 114 are mounted. The frame itself is supported on two tracks 115 and 116 near the top of the pit, as shown best in Fig. 10. There is provided cross shafts 117, 118 5 projecting outside the frame, the ends thereof being provided with rollers 119 which rollers operate upon the tracks 115, 116, thereby effecting a support of the unit for limited longitudinal movement to the right and left, as seen in Fig. 9. 10 Limiting this movement are springs 120 against which the entire frame reacts when driving against the main conveying chain, as will later appear more fully.

Continuing with the description of the driving 15 means on the frame 111, a gear 121 on the output shaft of the gear box 114 is meshed with a larger gear 122 which drives the shaft 123 projecting upwardly through suitable bearings 124. The end of the shaft 123 has secured thereto a 20 sprocket wheel 125. To provide another sprocket to complete a caterpillar drive, a shaft 126 is mounted for rotation in suitable bearing 127 and has secured at its upper end a sprocket 128. The sprocket wheels are sufficiently spaced to allow 25 for the operation of a caterpillar chain which is not shown in Fig. 9 but in the assembly view of Fig. 1, a caterpillar chain 129 is shown for operation around sprockets 125 and 128, to mesh with and drive the chain 24, guide rollers 130 30 being provided.

The mechanism assuring smooth engagement of the caterpillar chain with the driving chain is of the type shown in a copending application Serial No. 52,804. Unique to the present construction, however, as shown at 131 in Figs. 9 and 10, one of the tracks 22 is partially cut away and the caterpillar drive placed at a proper height to mesh with the conveying chain 24 midway between the tracks (see Fig. 1). By this cut 40 out construction of the track the conveying chain 24 can be supported at not too great a distance from the centerline of truck wheels 32 (see Fig. 4).

When multiple drives are used, the entire driv- 45 ing unit is mounted with limited longitudinal freedom and the springs 120 are provided in such location (see Fig. 1) that the reaction of the drive is taken by the springs 120. By a mechanism, which is not shown and which forms 50 no part of the present invention, the speed changing unit 113 is actuated by the aforementioned longitudinal movement of the frame, to compensate for change in driving load between the several driving units. 55

Operation

As previously mentioned, this conveyer system is adapted for use where steady operation is a primary requirement. The tracks located on 60 the floor form a steady foundation for the system and the two wheeled trucks, each of which is individually connected with the conveying chain operating between the tracks, makes up a compact close-coupled unit. In fact, the trucks 65 in reality are appendages of the chain system following it positively and also supporting said chain on the tracks with the result of substantially eliminating intermittent and jerky motion to be expected when a series of truck units is 70 pulled from a single chain connection. This unity of construction is followed out further when pallets 25 are placed on the trucks 23, thus connecting together a pair of the trucks 23 and providing a carrying platform relative- 75

ly close to the tracks and the conveying chain. It is also noted that the driving force exerted by the driving units is not materially offset below the plane of the tracks. The result is, in effect, 5 a platform mounted upon a moving chain, all solidly supported and rolling upon a track exceptionally free from vibration.

When a load carrying unit, as shown in Fig. 2, rounds a curve in the line of travel the trucks 10 23, turn about pins 47, which secure the ends of said pallet 25 to said trucks, the smooth under surface of the pallet allowing the washers 35 to slide thereon. Meanwhile the chain 24 follows the curve defined by the guide rollers 80 (see 15 Fig. 5), the chain being guided in such manner that each link to which a truck shaft is connected is substantially tangent to the curve and consequently the truck shaft is radial to the curve thereby eliminating any binding of wheel flanges 20 on the tracks which was objectionable in prior constructions. Considering the connection between the truck and chain, as shown in Figs. 3 and 4, it will be apparent on consideration that any variation from a true tangent position of a 25 chain link to which a truck 23 is attached would cause a tendency to bind the wheels on the curve by the turning effect of the chain, this tendency being minimized in the guide roller construction employed. As a further refinement, however, a 30 special construction is employed wherein tube 37 is given a substantial clearance on shaft 31 as shown in Figs. 3 and 4, thereby eliminating any binding tendency which still remains. It is also noted that clearance is allowed at the ends of 35 tube 37 between said tube and the adjacent pair of angles 34. Both the above clearances, as above explained, allow a limited movement of tube 37 on shaft 31 to permit compensation for slight variation in chain operation thereby eliminating 40 any binding tendency which still remains and which would otherwise produce objectionable vibrations. This clearance is an important feature of the construction contributing to produce the desired result of smooth operation.

The spring take-up construction shown in Figs. 1, 5, 6 and 7 results in holding the chain to the tension exerted by the spring mountings 88 which tend to move the entire platform 60 toward the left as shown in Figs. 1 and 5. Such a spring take-up keeps the chain properly taut and also serves to damp out vibrations which would otherwise be transmitted through the chain. Smooth operation on the curves is further assured by the positive guide for both open and closed links 55 of the chain by the shape of guide rollers 80 which provide a V-shaped guide at the center of each roller for the closed links of the chain and provide also a projection on each roller which fits into the open links of the chain.

It has previously been mentioned that developments in the conveyer art relative to driving units which automatically control the rate of conveyer travel has materially improved conveyer performance, especially as regards smooth and steady operation. However, further improvement has definitely been accomplished by the combination herein set forth which minimizes factors causing uneven operation and also tends to damp out such minor surging as may be set up.

Although the invention has been described as applied to a specific installation, it is understood that certain variations and modifications may be employed without departing from the fundamental principles as indicated by the scope of the following claims.

I claim:

1. In a conveyer system, a track having straight and curved sections, a conveying chain mounted for operation parallel with said track, said chain having link sections of varying shape, roller guides defining a path for said chain parallel with a curved section of said track, a projection pattern on the circumference of said rollers so formed that a guide for one section of said chain is effected in the central portion of said projection pattern and a guide for another section of said chain is effected by the outer edges of said projection pattern. 5 10 15

2. In a conveyer, a track, a load carrying unit for operation on said track comprising a pair of wheeled trucks each having an axle, a platform having a smooth under surface supported on said trucks, a pair of swivel connections between said platform and said trucks located centrally and substantially in a vertical plane through the axle 20 of each of said trucks, thrust washers projecting upwardly from said trucks spaced outwardly from and around said swivel connections and contacting the smooth under surface of said platform thereby allowing relative sliding movement 25 between said platform and the upwardly projecting washers on said trucks to allow pivotal movement of said trucks about said swivel connections.

3. In a conveyer, a conveying chain, a guide for defining the path at a curve in the line of travel 30 comprising, a plurality of rollers mounted inside said curve and tangent to the desired path of travel, an annular projection formed on each of said rollers forming a V-shaped guide at its center for the closed links of the conveying chain and 35 said projection being of a width to fit into the open links of said chain.

4. In a conveyer, a conveying chain, a plurality of wheeled trucks, a plurality of load carrying platforms one supported on each pair of said trucks, and connections from each of said trucks to said conveying chain, and swivel connections between each truck and its platform located in substantial vertical alignment with said chain connections. 45

5. In a conveyer, a plurality of wheeled trucks, axles for said trucks, a load carrying platform supported by each pair of said trucks, a swivel connection between said trucks and platform located centrally of each of said trucks and in a vertical plane through the axle of each of said trucks, and a plurality of flat supports on each of said trucks symmetrically spaced about said swivel connection for supporting said platform in a horizontal plane while permitting movement 55 between said truck and platform about said swivel.

6. In a conveyer, a conveying chain, a plurality of wheeled trucks, axles for said trucks, a plurality of load carrying platforms one supported on each pair of said trucks, and connections from each of said truck axles to said conveying chain forming the sole means of vertical support for said chain. 60

7. In a conveyer, a conveying chain, a plurality of wheeled trucks, a load carrying platform supported by each pair of said trucks, a swivel connection located centrally of each of said trucks securing said platforms on said trucks, and a connection from each of said trucks to said chain located in substantially vertical alignment with said swivel connection. 65 70

8. In a conveyer, a conveying chain, a plurality of wheeled trucks, a plurality of load carrying 75

- platforms, one supported on each pair of said trucks, swivel connections between each truck and its platform, and connections from each of said trucks to said conveying chain located in 5 substantial vertical alignment with said swivel connections and having sufficient lost motion therein to allow relative movement between said chain and said truck when operating on a curve in the line of travel.
- 10 9. In a conveyer system, a truck having straight and curved sections, a conveying chain mounted for operation parallel with said track, a support

for a curved section of said track mounted for limited movement parallel with a straight section of said track, roller guides for said conveying chain mounted on said support and located inside a curve parallel with said track with their peripheries tangent to said curve, adjustable resilient means for fixing the location of said support with a limited freedom of resilient movement thereby to provide for adjusting the tension on said chain and to assure smooth operation thereof. 10

NORMAN H. PREBLE.
